CLAIM

The ornamental design for a front face of a vehicle wheel, as shown and described.

DESCRIPTION

FIG. 1 is a front view of a front face of a vehicle wheel according to our novel design;

FIG. 2 is a perspective view of the front face of a vehicle wheel; and,

FIG. 3 is a section view taken along line 3—3 in FIG. 1. Features shown in dash lines depict the environment and do not form part of the claimed design.
